UNITED STATES PATENT OFFICE.

THOMAS BELLWOOD, OF METHUEN, AND HOLLAN GARTH, OF LAWRENCE,
MASSACHUSETTS.

CONDENSER-GUIDE.

1,130,467.

Specification of Letters Patent.

Patented Mar. 2, 1915.

Application filed March 30, 1911. Serial No. 617,937.

To all whom it may concern:

Be it known that we, THOMAS BELLWOOD, a citizen of the United States, residing at Methuen, and HOLLAN GARTH, a citizen of the United States, residing at Lawrence, both in the county of Essex and State of Massachusetts, have invented certain new and useful Improvements in Condenser-Guides, of which the following is a specification.

Our invention relates to drawing machinery more particularly for use in the manufacture of worsted yarn. It is intended to be attached to such machines as cone slubbers, dandies, reducers, slubbers, finishers, weigh boxes, first and second drawing boxes or to any other machines of a similar type. In such machines, a plurality of ends of sliver pass together through the back rolls so called and over carrier rolls to the front rolls which deliver them to fliers upon which they are twisted. Between the back rolls and the front rolls, the sliver is drawn out and in the usual form of machine it is found that it is spread out to such an extent that it loses some of its cohesion. On account of this, either from electrical action or for some other reason, certain fibers or flyings adhere to the front rolls and, if not removed, eventually accumulate and later come off in bunches. Such bunches being worked into the yarn form imperfect work or slubs. To remove these flyings there is often located below the lower front roll, which is usually of metal and fluted, what is known as a rubber which catches the flyings or rubber waste so called. This rubber must be frequently removed and cleared from time to time by hand. The upper front roll which is usually of leather can be cleaned from the front of the machine by hand after sufficient waste has accumulated. On some machines, a clearer bar is used in front of the upper front roll so as to bring the sliver away from the lower front roll thereby reducing the tendency for the rubber waste to stick thereto. It is supposed also to prevent waste or flyings from sticking to the top roll.

In the drawings, Figure 1 is a section from the side of the back and front rolls of a finisher. Fig. 2 is a perspective view of the same with the upper front roll removed. Fig. 3 is a top view in detail of the carrier rolls. Fig. 4 is a detail in perspective showing our condenser guide and manner of at-

taching it. Fig. 5 is a detail view from the back of our preferred form of adjustable condenser guide. Fig. 6 is a side view of the same. Fig. 7 is a front view of another form of condenser guide.

10, 11, 12 and 13 are the back rolls.

14 is the upper leather covered front roll and 15 is the lower front fluted metal roll. Between the front rolls and the back rolls are the revolving carrier rolls 20, 21, 22 and 23 which support the sliver A and assist in carrying it along to the front rolls. In these machines, a guide behind the back rolls and not shown but having a lateral movement moves the sliver from side to side so that it will not wear out any one part of the various rolls.

30 is the brace bar which extends between the stand sections of the machine as usually made.

75

Our device may consist of a wire condenser guide B such as is shown in Fig. 7. Such wire guide has parallel legs 40 and 41 which preferably are formed with bows 42 and 43 near the bottom and come together 80 to form an eye 44 through which loosely and through a hole 31 in the brace bar 30 just underneath the point where the sliver passes, extends a screw or pin 45. Such wire legs 40 and 41 may be adjusted toward and 85 from each other in a direction parallel with the front and back rolls by bending with pliers or with the fingers. The bows 42 and 43 facilitate such adjustment and they should be of flexible wire so that when bent 90 they will retain their new position.

We prefer to place our condenser guide between the revolving carrier rolls although it may be placed between the front carrier roll and the front rolls if the stock used 95 has a long staple. With short staple however, the front carrier roll must be so near the front rolls that our condenser guide must be placed between the carrier rolls.

Our condenser guide is preferably so pivoted that it can move from side to side as shown by the dotted lines in Fig. 7 to accommodate itself to the movements of the sliver. It might however, be so arranged as to slide sidewise if desired.

We prefer the form of adjustable condenser guide C shown in detail Figs. 5 and 6. The base 50 which has a pivot hole 51 has also a leg 52 and a shoulder or arm 53 at right angles thereto and has also an 110

adjusting slot 54 at right angles to said leg 52. The movable leg 55 corresponds with leg 52 and has a ridge 56 adapted to slide along shoulder 53. It is bolted to the 5 arm 53 by means of a bolt 57 which passes through slot 54 and has a nut 58 which may be loosened or tightened. By means of bolt 57 and nut 58 the distance between legs 52 and 55 may be varied. Preferably a bolt 10 60 passes through a hole 62 in brace bar 30 and through a sleeve 61 which passes loosely through a hole 63 in base 50 of guide C. A nut 64 screwed on bolt 60 and against sleeve 61 holds the parts in position. Guide C 15 can rock freely on sleeve 61.

By the use of our device, the sliver is condensed laterally and thus passes between the front rolls and leaves them in a much more compact form. The result of this is that 20 there is practically no rubber waste and the rubbers as well as the clearer bars can be dispensed with entirely. As our device prevents flyings or rubber waste, there are no slubs or bunches in the yarn after it is 25 twisted by the flier D.

Our device consists essentially of a thin 30 guide with thin legs adjustable toward and from each other in a direction parallel with the front rolls and back rolls and located between such rolls, said guide preferably

being pivoted to the brace bar to swing laterally in a plane parallel with the axes of said rolls.

Our device may be used on any machine for drawing worsted sliver or it may be used on any machine for drawing any fiber such as cotton, ramie, or silk.

What we claim as our invention and desire to cover by Letters Patent, is:

In a machine for drawing worsted sliver, 40 the combination of back rolls, front rolls, and carrier rolls between them, with a brace bar below the carrier rolls, and a condenser guide which comprises a base with a leg fixed thereto and a shoulder in 45 which is a slot at right angles to said leg together with a movable leg having a ridge adapted to slide along the shoulder and adjustably attached to the base by means of a bolt which passes through the slot therein 50 and a nut, said condenser guide being so pivoted to the brace bar as to swing laterally as described.

In testimony whereof we hereto affix our signatures in presence of two witnesses.

THOMAS BELLWOOD.
HOLLAN GARTH.
